UNITED STATES PATENT OFFICE.

VALENTY WROCLAWSKI AND MICHAEL KOLASINSKI, OF CHICAGO, ILLINOIS.

DRAFT-GEAR.

1,107,396.

Specification of Letters Patent. Patented Aug. 18, 1914.

Application filed October 16, 1911. Serial No. 655,065.

To all whom it may concern:

Be it known that we, VALENTY WROCLAWSKI and MICHAEL KOLASINSKI, both citizens of the United States of America, and residents of Chicago, county of Cook, State of Illinois, have invented certain new and useful Improvements in Draft-Gears, of which the following is a specification.

The main objects of this invention are to provide an improved form of draft gear for railway cars, and the like, equipped with shock absorbing means; to provide an improved construction and arrangement of the shock absorbing means and the connections thereof to the car coupler; to provide improved means for connecting together the shock absorbing means at opposite ends of the car so as to multiply the effective resistance and apply it to best advantage; and to provide an improved construction of the supporting members and improved mounting of the draft gear parts thereon, so as to permit the end sill of the car to be removed without dismantling the entire gear.

An illustrative embodiment of this invention is shown in the accompanying drawings, in which:—

Figure 1 is a side elevation of a draft gear constructed according to this invention. Fig. 2 is a plan view of the same, parts thereof being broken away to more clearly illustrate the construction. Fig. 3 is a sectional view taken on the irregular line A—A of Fig. 2. Fig. 4 is a longitudinal sectional view taken on the line C—C of Fig. 2. Fig. 5 is a similar view through one of the side cushioning members taken on the line B—B of Fig. 2.

In the construction shown in the drawings, the supporting element for the draft gear comprises members 1 and 2, preferably adjacent the sills, in the form of I-beams extending longitudinally of the car and forming a part of the construction thereof and providing guideways for the shock absorbing device. A spacer block 3 is secured between the I-beams 1 and 2 by means of a pin 4. A drawbar 5 is slidably mounted between the I-beams 1 and 2 at their outer ends and carries a car coupler 6. A shock absorbing device is interposed between the spacer block 3 and the drawbar 5 for cushioning the thrust. This shock absorbing device comprises blocks 7, 8 and 9 slidably mounted between the I-beams 1 and 2 and

spaced apart by interposed springs 10 and 11. The blocks 7 and 9 are respectively provided with studs 12 and 12', fitting in sockets in the spacer block 3 and drawbar 5, and being of sufficient length to prevent the disengagement of the blocks 7 and 9 respectively from the block 3 or drawbar 5 during any relative movement thereof. Hollow slides 13 are respectively mounted to slide in the channels formed by the outer flanges of the I-beams 1 and 2. Blocks 14, 15 and 16 are slidably mounted within the slides 13 and spaced apart by interposed springs 17 and 18 so as to be located in substantially transverse alignment with each other and with the drawbar 5 and blocks 8 and 9, respectively. Each of the blocks 14 is connected with the drawbar 5 by a key or cross-tree 19, rigidly secured in slots in the blocks 14 and drawbar 5. The pairs of blocks 15 and 16 are similarly secured to the respective blocks 8 and 9 by means of keys 20 and 21. The keys 19, 20 and 21 are secured against dislodgment by means of pins 22 inserted into apertures in the keys outwardly of the slides 13. The I-beams 1 and 2 are provided with slots 23, which are of sufficient length to permit the desired range of movement of each of the keys, the key 19 being adapted to move in either direction and the keys 20 and 21 being adapted to move only in directions relatively opposite. The slides 13 are also provided with slots 24 so as to permit relative movement of the blocks supported in the slides, the keys 19 and 21 being normally urged to respectively opposite ends of the respective slots 24, and the key 20 being normally held centrally in the slots in the members 13. The ends of the slots 23 and 24 form shoulders for limiting the respective movement of the keys 20 and 21.

The slides 13 at opposite ends of the car are connected together by means of rods 25, so that when the drawbar 5 of one gear is pulled outwardly, both sets of springs in the opposite gear, and the rear set of springs in said one gear are brought under compression, as will hereinafter appear in describing the operation. The rods 25 have square heads 26 which are seated in sockets 27 and secured against disengagement therefrom by means of pins 28. The sockets 27 are longer than the heads 26, so as to allow a relative movement of the slides and rods in case the

drawbar is pushed inwardly. The rods 25 are also provided with turnbuckles 25^A by means of which they may be adjusted to take up slack.

5 The end sections 29 of the I-beams 1 and 2 are removably attached so that they may be disconnected from the I-beams, and the drawbar 5 removed by withdrawing the key 19 so as to permit the replacing of the end 10 sill 30 of the car without damage to the end sheathing.

The operation of the device shown is as follows: Normally, the parts are in the position shown in Fig. 2, so that with respect 15 to the I-beams 1 and 2 the key 21 is free to move only in the direction toward the right of the figure, the key 20 being free to move in the direction toward the left, and the key 19 being free to move in either direction.

20 When the drawbar 5 is pushed inwardly, the keys 19 and 20 are urged inwardly, thereby causing a movement of the blocks to which they are connected toward the blocks 9 and 16, which are held stationary by the key 21, thereby resulting in a compression of the springs 10, 11, 17, and 18. During this action of the shock absorbing device, the slides remain stationary by virtue of the arrangement of the slots 24.

25 30 When there is a pull on the drawbar 5, the key 19 transmits the pull to the slides 13 of the respective draft gear, and through the tension rods 25 to the slides on the draft gear at the opposite end of the car, which 35 latter slides cause the compression of the springs of the respective draft gear in a similar manner as when the springs are compressed by reason of a thrust on the drawbar of said respective draft gear.

40 45 During the movement of the slides 13, the key 20 is held against movement therewith, and effects the compression of the springs 11 and 18 through the movement of the key 21 toward the key 20. Thus, to a thrust on the drawbar 5, six springs are brought into action to resist the strain, and when there is a pull on the drawbar, nine springs are brought into action to resist the strain.

Although but one specific embodiment of 50 this invention is herein shown and described, it will be understood that numerous details of the construction shown may be altered or omitted without departing from the spirit of this invention, as defined by the 55 following claims.

We claim:—

1. A draft gear comprising a pair of members spaced apart, a hollow slide supported at the outside of each of said members, a plurality of blocks slidably mounted between said members and in said slides, said blocks being arranged in substantially transversely aligned sets and spaced apart longitudinally, resilient means interposed between the blocks in each longitudinal row, 60 a drawbar, keys connecting some of the blocks in transverse rows and slidably supporting said blocks and slides on said members, said slides and members being slotted to receive said keys, said slots being arranged so as to permit the compression of all of said resilient means when said drawbar is pushed inwardly, and to permit the compression of one set of said springs when said drawbar is pulled outwardly. 75

2. A draft gear comprising a pair of members spaced apart, a hollow slide supported at the outside of each of said members, a plurality of blocks slidably mounted between said members and in said slides, said 80 blocks being arranged in substantially transversely aligned sets and spaced apart longitudinally, resilient means interposed between the blocks in each longitudinal row, a drawbar, keys connecting some of the blocks 85 in transverse rows and slidably supporting said blocks and slides on said members, said members being slotted to permit the forward key to be relatively moved therein in both directions, and the rearward and middle keys to be relatively moved therein only in relatively opposite directions, and said 90 slides being slotted to permit said forward and rearward keys to be relatively moved therein only in relatively opposite directions, and permit said middle key to be relatively moved therein in both directions for the purpose specified. 95

Signed at Chicago by me, VALENTY WROCLAWSKI, and by me, MICHAEL KOLASINSKI, this 4th day of October 1911.
